UNITED STATES PATENT OFFICE.

JOSEPH BENZION, OF NEW YORK, N. Y.

TUMBLER-WASHER.

1,116,006.

Specification of Letters Patent.

Patented Nov. 3, 1914.

Application filed November 12, 1913. Serial No. 800,544.

To all whom it may concern:

Be it known that I, JOSEPH BENZION, a citizen of the United States, residing in the borough of Manhattan, New York city, county and State of New York, have invented certain new and useful Improvements in Tumbler-Washers, of which the following is such a full, clear, and exact description as will enable any one skilled in the art to which it appertains to make and use the same, reference being had to the accompanying drawings, forming part of this specification.

My invention relates to certain improvements in machines for washing tumblers by means of jets of water, and more particularly to the type of machine in which the tumbler is held with its mouth down and is then depressed in order to turn on the water.

One of the principal objects of my present invention is to provide a machine of this class with a combined spraying device and guard, the purpose of the guard being to prevent the water from splashing the operator.

The invention also seeks to provide a very substantial and durable spring-seated support for the vertically movable spraying device.

With these and other objects in view my invention consists in the various novel and peculiar combinations and arrangements of the several different parts of the machine, all as hereinafter fully set forth and then pointed out in the claims.

I have illustrated a type of my invention in the accompanying drawings, wherein:

Figure 1 is a vertical sectional view of my improved tumbler-washer. Fig. 2 is a top plan view of the machine with part of the cup-shaped spraying device and guard broken away and in horizontal section. In this view a portion of the drain-pan is also shown as broken away. Fig. 3 is an enlarged central vertical sectional view of the machine with the upper portion of the combined sprayer and guard broken away, likewise the portions of the drain-pan. Fig. 4 is a similar view to that shown in Fig. 3 of the spring-seated sliding valve but with the valve shown in closed position. Fig. 5 is a horizontal sectional view of the machine the plane of the section being indicated by line 5-5 in Fig. 3. Fig. 6 is a horizontal

sectional view of the parts shown in Fig. 3, the plane of the section being indicated by line 6-6 in said figure.

Referring to the drawings in which like numbers of reference designate like parts throughout, 1 is the water supply pipe which is attached to a vertical tube 2, the lower end of which is provided with an external screw-thread for connecting it with the water pipe. The upper end of the tube 2, is enlarged so as to provide a valve-chamber 3. This tube is provided with an external flange 4, the under side of which rests upon the inner surface of the concave drain-pan 5, in the center of which is formed an opening 6, through which the tube 2, extends, and with which it forms a watertight joint. The upper end of the tube 2, is provided with an external flange or lip 7, upon which rests the center part of the perforated drip-plate or tray 8, the rim or periphery of which rests upon a shoulder 9, formed near the upper edge of the concave pan 5, the upper edge of the pan being provided with a rim or gallery 10. The center of the drip-plate 8, is formed with a perforation 11, through which extends the upper end of the tube 2. A tubular coupling 12, having its lower end externally threaded is screwed into the interior thread on the upper end of the tube 2, and this coupling is provided with a peripheral flange 13, which bears upon the upper surface of the drip-plate 8, around the opening 11, therein and serves to clamp the drip-plate 8, against the flange 7, on the tube, a soft washer 14, being interposed between the end of the tube and the flange on the coupling.

The lower end of the coupling 12 extends into the valve-chamber 3, in the tube and forms a circular valve-seat 15, for the vertically sliding tubular valve 16. This valve 16, comprises a tubular member which is closed at 17, at its lower end and is provided near such end with an external flange 16a, upon which is placed a soft washer 18, which takes against the valve-seat 15. This valve is provided with a series of lateral ports 19, four of such ports being shown in this construction. These ports are arranged radially and place the exterior of the valve in communication with the hollow interior of the valve and its stem 20, the upper end of which is

formed with an external screw-thread which coöperates with an internal thread in the central perforation 21, formed in a fitting 22, which is T-shaped in cross section, and upon which is mounted the combined cup-shaped sprayer and water-guard 23, as hereinafter described.

The upper part or head of the fitting 22, is provided with oppositely arranged laterally extending ducts 24, which register with corresponding openings 25, in the wall of the tubular valve-stem 20, and the water coming from the valve and passing into the valve-stem is supplied through the ducts 24, to the interior of the cup-shaped spraying device. At the same time the water is supplied from the upper open end of the valve-stem to the interior of the nozzle 26, which is arranged centrally within the bottom of the cup-shaped sprayer and is provided at its upper end with spraying openings 27. This nozzle 26, has at its lower end a screw-thread which fits upon a corresponding external thread on the upper end of the tubular valve-stem 20, and the lower end of the nozzle when screwed down tight bears firmly against the interior of the bottom of the cup-shaped sprayer 23.

The downwardly projecting stem portion of the fitting 22, is tubular in shape and surrounds and makes a sliding fit with the upper and reduced end 28, of the coupling 12, and the lower end of this tubular part 30, when in its lowest position rests against an annular shoulder 29, on the coupling, while at the same time the upper end of the coupling 29, abuts against the interior part 30, of the fitting as indicated in Fig. 3. The sliding valve and its stem, and likewise the parts connected with the stem are acted upon by the upwardly pressing coil spring 31, the lower end of which rests against an annular shoulder 32, within the tube 2, while the upper end of the spring bears against the peripheral flange 16^a, of the valve. Normally the spring 31, keeps the valve forced upwardly so as to close its ports 19, as shown in Fig. 4. When, however, the valve-stem is depressed by means of the connected spraying cup, the parts are moved into the positions shown in Fig. 3, and the valve-ports 19, are opened so as to supply the sprayer and nozzle with water. The telescoping joint formed between the upper end 28, of the coupling 12, and the tubular stem of the fitting 22, provides a very substantial bearing and support for the connected parts, and as the fitting 22, may be made in a single casting, it adds to the strength of this part of the device.

The bottom and the sides of the cup-shaped sprayer 23, are made hollow so as to provide a water-space 33, and all parts

are in communication with the laterally extending ducts 24 of the fitting 22, and this water space is closed at its upper end and at a point indicated at 34, in Fig. 1. The inner wall of the cup-shaped vessel is provided with a series of perforations 35, which are arranged at different points of the wall, as desired, and are designed to project the water inwardly against the exterior of the contained glass or tumbler 36, when the same is placed in inverted position with the lower end of the tumbler resting upon the bottom of the vessel, as indicated in Fig. 1, the position of the inverted glass being also shown in dotted lines in Fig. 3. At the same time the exterior of the tumbler is sprayed by the jets of water by the openings 35, in the cup-shaped vessel, and the jets of water are also projected against the interior of the tumbler by means of the nozzle 26, as indicated in Fig. 1. By having the spray cup of greater depth than the body of the tumbler, as shown in the drawings, some of the spraying holes may be arranged above the level of the inserted tumbler without liability of the spray escaping from the cup.

In the construction herewith shown, the cup-shaped sprayer 33, is made of two spun metallic members, 33^a and 33^b, one fitting within the other, with a space between the bottoms thereof and with a very narrow space between the side walls of the two members, and as the spraying openings 35, are also comparatively small, this gives a high pressure to the water projected from the spraying openings, and this is an important feature of this particular form of cup-shaped sprayer. These two members being placed one within the other, the upper edges where they come in contact at 37 are soldered together to form a watertight joint around the edge of the cup. The inner wall or member of the cup is formed near its upper end with an annular bend or rib 38, the under side of which is provided with a series of perforations 35, for spraying the water downwardly toward the center of the cup. The two metallic members forming the cup are secured together at their bottoms by the head or upper part of the fitting 22, these parts being brazed together, as indicated more particularly in Fig. 3, the head of the fitting extending practically across the bottom of the cup as indicated in Figs. 1 and 5. As the head of this fitting is practically a solid piece, it strengthens the cup at its central point of support. Upon the top of the fitting is formed a small boss 50, which surrounds the central perforation therein and which extends through the opening 51 formed in the bottom of the inner cup-shaped member 33^b, and this inner member is clamped against the upper

end of the fitting by means of the lower end 52, of the nozzle 26.

A series of drip-holes 39, are formed 5 through the double walls of the bottom of the cup-shaped vessel, and also through the interposed head part of the fitting 22, as indicated in Figs. 1 and 2, and as the fitting is brazed to the parts of the walls with which it comes in contact, the water passing 10 through the drip-holes in the cup-shaped vessel cannot find its way into these joints, and the water-space 33, is likewise cut off from communication with the drip-holes 39.

The water after having been sprayed 15 upon the tumbler passes as waste water from the bottom of the cup-shaped vessel through the drip-holes 39, and falls upon the drip-pan 8, and passes thence through the same into the concave pan 5, from whence it es- 20 capes by a waste-pipe 40.

From the foregoing description, it will be readily understood that normally the valve is closed by means of its spring as shown in Fig. 4. The operator inserts an inverted 25 glass within the cup-shaped sprayer placing it in the position over the nozzle as indicated in Fig. 1, and as he bears down upon the tumbler, the spring 31, is compressed as shown in Figs. 1 and 3, and the water is then 30 permitted to pass into the valve-ports 19, and thence through the tubular valve-stem by way of the openings 25, the ducts 24, and the water-space 33, to the spraying openings 35, in the interior wall of the sprayer, and 35 at the same time it is supplied to the interior of the nozzle 26 from the upper open end of the valve-stem, and the glass is thus sprayed simultaneously upon the interior and the exterior. At the end of the spraying opera- 40 tion, the pressure upon the tumbler being released, the spring 31, forces the valve into closed position and cuts off the supply of water thereby shutting off the spray. In this operation, while a large number of jets 45 may be used in the spraying device, there is no liability of any of the sprays escaping to the exterior of the vessel or of the water splashing so as to reach the outside of the vessel and splashing the operator. It will 50 be noted that this cup-shaped vessel performs the function of a sprayer which can be made to supply a very large number of water jets, and also the function of a guard for preventing the escape of any of the 55 spray.

Having thus described my invention, what I claim and desire to secure by Letters Patent is:

1. In a tumbler-washing machine, the 60 combination of an open-top vertically reciprocating combined guard and spray cup having its exterior imperforate and having a water-chamber in its walls and its interior provided with spray-openings dis- 65 posed at various points over its interior

circumference, whereby the sprays are directed inwardly from practically all directions, a water-supply and a valve controlling the same and provided with a spring acting to keep the valve normally closed, 70 said water-chamber and valve chamber being in communication, and connections between said spray-cup and valve serving to open the valve and operate the spray upon the depression of said spray-cup, substan- 75 tially as described.

2. In a tumbler-washing machine, the combination of a vertically reciprocating spray-vessel in which an inverted tumbler may be placed and by which it may be de- 80 pressed, a spring acting to keep said vessel normally in elevated position, the said vessel comprising two sheet-metal cup-shaped members nested together with a water-chamber between them and said chamber 85 closed at its top, the outer member being imperforate and the inner member being provided with spray-openings for injecting jets of water inwardly into said vessel, a spray-nozzle mounted in the bottom of said 90 inner member, a water-supplying pipe passing up through the bottoms of both of said members and having the said nozzle mounted upon the upper end thereof and the said pipe being in communication with said nozzle and said water-chamber, a valve casing and a valve therein, the said pipe being connected with and actuating said valve and being mounted to reciprocate with respect to said valve-casing, substantially as and 95 100 for the purpose set forth.

3. In a tumbler-washing machine, the combination of a vertically reciprocating spray-vessel in which an inverted tumbler may be placed and by which it may be de- 105 pressed, a spring acting to keep said vessel normally in elevated position, the said vessel comprising two sheet metal cup-shaped members nested together with a comparatively narrow annular water-chamber be- 110 tween the same and a connected water-space between the bottoms thereof, the outer member being imperforate and the inner member being provided with spray-openings for injecting jets of water inwardly 115 into said vessel, a water supply and a valve controlling the same, and connections between said valve and spray vessel, the said water-space between the bottom of said cup-shaped members being in communica- 120 tion with the said valve-chamber, substantially as described.

4. In a tumbler-washing machine, the combination of a water supply, a valve controlling said supply and provided with a 125 reciprocating tubular stem having at its upper part lateral openings, a spring acting to normally keep the valve closed, a spray-device having its bottom chambered for the passage of water therethrough, a T-shaped 130

fitting having its head secured in said chambered bottom of the spray-device and reinforcing and supporting said device, the stem of said fitting being tubular, a tubular part projecting from the chamber of said valve within the tubular stem of said fitting and making a sliding fit therewith, the said valve stem extending through said tubular part on the valve-chamber and thence through the head of said fitting, the head of said fitting being provided with lateral ducts in communication with the chamber in the bottom of said spray device, and registering with the lateral openings in said valve stem, substantially as described.

5. In a tumbler-washing machine, the combination of a vertically reciprocating spray vessel in which an inverted tumbler may be placed and by which it may be depressed, a spring acting to keep said vessel normally in elevated position, the said vessel comprising two sheet-metal cup-shaped members nested together with a water-chamber between the sides and bottoms thereof and closed at its upper end, said inner member being provided with spray-openings for projecting jets of water inwardly into said vessel, a water-supply and a vertically reciprocating pipe controlling the flow of said water, a fitting having a horizontal head placed between the bottoms of said members and secured to each and reinforcing them, the said head of the fitting being provided with lateral ducts leading into said water-chamber and the said pipe extending through and secured to the said head and provided with lateral openings opening into said ducts respectively, whereby upon the depression of said vessel 40 and its pipe the water may pass from said pipe through said fitting into said water-chamber to produce the spray.

6. In a tumbler-washing machine, the combination of a drain-pan, a drip-plate spaced from the bottom of said pan, a water-pipe extending up through the bottom of said pan, a valve chamber mounted upon said pipe within said pan and a valve in said chamber controlling the flow of water, a projection upon the valve chamber adapted to receive and support said drip-plate, a detachable tubular coupling mounted in the upper end of said valve chamber and provided with an external projection engaging said drip-plate and clamping it against the projection on said valve-chamber, a reciprocating valve-stem connected with said valve and sliding within said coupling and a spray-device connected with said valve-stem, substantially as described.

7. In a tumbler-washing machine, the combination of a spray-device having a chambered bottom, a water-supply connected with said chambered bottom of the spray device and a valve controlling said

supply, a vertically movable tubular valve-stem having its interior in communication with the valve-ports and provided with lateral openings, a fitting having its upper portion secured within the chambered bottom of said spray-device and its lower part extending through the bottom thereof, the upper part of said fitting being provided with lateral ducts registering with said lateral openings in the tubular valve-stem, a coupling secured to the valve-casing through which coupling extends said valve-stem, the bottom of said spray-device being provided with drip-holes extending through the wall thereof and the upper part of the fitting, and a spring acting to keep said valve normally closed and the said valve being opened against the action of the spring by the depression of the inverted tumbler within the vessel, substantially as described.

8. In a tumbler-washing machine, the combination of a vertically reciprocating spray-device adapted to receive an inverted tumbler and by which the spray-device may be depressed, a spring acting to keep said spray-device normally in elevated position, a valve chamber and a water-supply connected therewith, a reciprocating tubular valve-stem adapted to place the valve-chamber in communication with said spray-device when the valve is open, a detachable tubular coupling mounted within the upper end of the valve-chamber and the lower end of said coupling constituting an annular valve seat within said chamber, the upper end of said coupling being provided with an extension and the said valve-stem sliding within said coupling, the said spray-device being provided with a depending tubular part with the interior thereof making a sliding fit with the exterior of the extension on said coupling, substantially as described.

9. In a tumbler-washing machine, the combination of a drain-pan having an outlet and provided with an internal shoulder, a drip-pan resting on said shoulder, a reciprocating spray-device provided with a valved water-supply connection passing up through said pan and plate and comprising a valve-casing disposed between said pan and plate and serving as a support for the central portion of said plate, substantially as described.

10. In a tumbler-washing machine, the combination of a vertically reciprocating spray-vessel in which an inverted tumbler may be placed and by which it may be depressed, a spring acting to keep said vessel normally in elevated position, the said vessel comprising two sheet metal cup-shaped members nested together with a comparatively narrow annular water-chamber between the same and a connected water-space between the bottoms thereof the outer member being imperforate and the inner member

being provided with spray-openings for injecting jets of water inwardly into said vessel, and being further provided with a circumferential rib having formed therein 5 downwardly and inwardly directed spray-openings, a water supply and a valve controlling the same, and connections between said valve and spray-vessel, the said water-space between the bottom of said cup-shaped members being in communication

with the said valve-chamber, substantially as described.

In testimony whereof, I have hereunto set my hand in the presence of the two subscribing witnesses.

JOSEPH BENZION.
